UNITED STATES PATENT OFFICE.

HERBERT O. ROSS, OF ST. LOUIS, MISSOURI.

RACK OR FILE FOR CORRESPONDENCE AND THE LIKE.

Application filed December 31, 1919. Serial No. 348,613.

To all whom it may concern:

Be it known that I, HERBERT O. Ross, a citizen of the United States, residing at the city of St. Louis, State of Missouri, have 5 invented a certain new and useful Improvement in Racks or Files for Correspondence and the like, of which the following is a specification, reference being had to the accompanying drawings, forming a part 10 thereof.

This invention relates to a certain new and useful improvement in racks or files for correspondence and the like.

The chief object of my present invention 15 is to provide a rack adapted to rest upon a desk or other such support and wherein letters, papers, documents, and the like pertaining or relating to different matters or to different departments of a business may be 20 conveniently filed, on being assorted, for distribution in due course to the particular departments or for ready accessibility for use in connection with the particular matters.

25 Other objects of my invention are to provide a rack or file especially of the kind and for the purpose stated which is comparatively simple and inexpensive in form and construction and neat and attractive in appearance, and in which the number of compartments, and hence the capacity, of the rack or file may be increased or decreased with facility and convenience to meet the 30 needs or requirements of any particular use 35 or installation.

With the above and other objects in view, my present invention resides in the novel features of form, construction, arrangement, and combination of parts hereinafter 40 described and afterwards pointed out in the claims.

In the accompanying drawings,

Figure 1 is an end elevational view, partly broken away and in section, of a rack or file 45 constructed in accordance with and embodying my invention;

Figure 2 is a side elevational view of the same, partly in section;

Figure 3 is a broken or fragmental plan 50 view of the blank from which the base of an intermediate section or unit is formed;

Figure 4 is a fragmental perspective view of one of the intermediate sections or units of the rack;

Figure 5 is an enlarged fragmental detail 55 sectional view, showing the preferred means by which two sections or units of the rack are connected detachably together;

Figure 6 is a fragmental perspective view of one of the end sections or units of the 60 rack;

Figure 7 is a similar view of the other or opposite end section or unit of the rack; and

Figure 8 is a broken fragmental plan view 65 of the blank from which the base of an end section or unit is formed.

Referring now more in detail to the said drawings, in which like reference characters refer to like parts throughout the several 70 views, the rack or file is made up of and comprises a pair of end sections or units and, generally in practice, one or more intermediate sections or units.

Each intermediate section or unit of the 75 rack comprises a base A, which, as seen especially in Figure 1, is approximately of inverted U-shape in cross section. This base A is preferably formed from a single blank of material, such as, for instance, sheet 80 metal, of suitable dimensions for the finished section, the blank having the shape indicated in Figure 3. The blank is first cut or slit along the short dash lines a—a, and then lengthwise bent along the dotted 85 lines b—b to provide the floor-member 1 and the downwardly disposed legs or side portions 2—2. The blank is then bent downwardly at its ends, as along the dotted line c, to provide the front wall portions 3—3, 90 which, in turn, are bent or curled upwardly, as along the dotted line d, to provide base-seats or channels 4 of index-card receiving pockets for the section. The blank is then suitably bent or curled inwardly, as along 95 the dotted lines e, to provide the oppositely disposed ways 5 for co-operation with the channels or base-seats 4 in forming the index-card receiving-pockets for the sections.

Each end section or unit of the rack comprises a base B, which is formed in like manner to the formation of intermediate base

A from the blank illustrated in Figure 8. This latter blank is identically similar to the blank illustrated in Figure 3, except that one of the legs or side portions 2 is provided 5 preferably midway its length with an extension 6, which is bent upwardly, as along the dotted line f , to form a pocket for receiving cards or the like. Except as stated, the base B of the end sections is preferably identi- 10 cally similar to the base A of the intermediate sections. It might be here stated that, as seen in Figure 2, the side wall pockets 6 may, for convenience, be equipped or pro- vided with calendars or the like.

15 The one end section comprises a base B and upright panels or walls 7—7 of suitable material, such as, for instance, sheet metal, heavy card-board, beaver-board, or the like, which walls are disposed, as shown partic- 20 ularly in Figure 7, upon opposite sides of the base with their lower portions disposed in flatwise abutting position against the side- 25 portions 2 of the base, and to which base- portions the walls 7 are rigidly fixed pref- erably by means of eyelet-rivets or the like 30 8, the walls 7 being of any suitable height and having a length corresponding to the length of the base, as shown in Figure 2. Spot-welded or otherwise suitably fixed to 35 the outer face of one of the walls 7 of the end-section, are angle-members or the like 9, which serve both as supporting-braces for 40 the end section or unit and also to add an attractive finish to the rack.

45 Each intermediate section comprises a base A and but a single upright panel or wall 7, this wall 7 being disposed, as shown in Figure 4, along one only of the side- 50 portions 2 of the base and to which base- portions it is similarly fixed by rivets 8. The oppo- 55 site or free side-portion 2 of the base of the intermediate section is, however, provided with preferably square apertures or the like, as at 15, adapted to register with the eyelets 8 of an abutting or contiguous section or 60 unit, for purposes shortly appearing.

The other or opposite end section, as 65 illustrated particularly in Figure 6, is sub- 50 substantially similar in all respects to the inter- 70 mediate sections or units, as above de- 75 scribed, except that its upright panel or wall 7 is similarly, as in the other end sec- 80 tion first described, equipped or provided 85 with the supporting-braces 9, and a base 90 B is employed in lieu of the base A of the intermediate section, so as to likewise pro- 95 vide this end of the rack with a pocket 6.

In use or practice, should a rack of but 100 two compartments be desired, the same may 105 be conveniently formed of but two end sections, such sections being placed length- 110 wise side by side with the free side base- 115 portion of one end section abutting flatwise 120 against the inner wall 7 of the other end 125 section and the apertures 15 of the one sec- 130

tion registering with the eyelets 8 of the other section. By means then of suitable se- 135 curing-means, such as, for instance, bolts 12 passed through the registering apertures 15 and eyelets 8, and their fastening nuts 13, the sections are firmly detachably se- 140 cured together in connected relation to form the finished rack.

Should a rack of three compartments be 145 desired, an intermediate section is placed 75 between the end sections, the eyelets 8 of one end section registering with the apertures 15 of the intermediate section and the eyelets 8 of the intermediate section registering 80 with the apertures 15 of the other end sec- 85 tion, when, by means of bolts 12 and nuts 13, as shown in Figure 1, the several sections may be conveniently secured together, as shown, to likewise form the finished rack. In like manner, a rack or file of my inven- 90 tion may be built up or extended to include any desired number of intermediate sections and hence any desired number of compartments, the several sections being readily fas- 95 tened and connected together as before de- 100 scribed.

In each instance, whether the rack or file 105 be of two or more compartments, the co-op- 110 erating seats 4 and ways 5 provide at each 115 end of each compartment a readily ac- 120 cessible pocket for receiving an index-card, such as the card 14, for indicating to the 125 user the particular contents of the compart- 130 ment.

Thus I provide a rack or file well adapted 100 for the purposes stated and one whose ca- 105 pacity and number of compartments may, with convenience and facility and practi- 110 cally at will, be increased or decreased, as 115 may be desired, the rack not only being an 120 attractive addition to a desk, but also tend- 125 ing largely to increase the desk efficiency of 130 the user, and being one which may be inex- 135 pensively constructed and maintained.

I am aware that changes in the form, con- 140 struction, arrangement, and combination of 145 the several parts of my new rack or file may 150 be made and substituted for those herein 155 shown and described without departing from 160 the nature and principle of my invention.

Having thus described my invention, what 165 I claim and desire to secure by Letters Pat- 170 ent is:

1. A rack of the class described including, 175 as a unit, an upright wall and a one-piece 180 floor-member provided with approximately 185 right angular marginal side portions, the 190 wall being rigidly fixed flatwise at an end 195 to one of the side portions of the floor-mem- 200 ber, and the unit as a whole being adapted at 205 the other side portion of the floor-member 210 for detachable connection with an adjacent 215 unit.

2. A rack of the class described including 220 a plurality of compartment-forming units,

each unit comprising an upright wall and a one-piece floor-member provided with approximately right angular marginal side portions, the wall being rigidly fixed flatwise at an end to one of the marginal portions of the floor-member, in combination with fastening means having removable engagement with the other marginal portion of the floor-member for detachably securing the units together in connected relation. 10
In testimony whereof, I have signed my name to this specification.

HERBERT O. ROSS.
